[57] CLAIM

The ornamental design for a laminal tongue pocket for
footwear, as shown and described.

DESCRIPTION

FIG. 1 is a perspective view of a laminal tongue pocket
for footwear showing my new design;

FIG. 2 is a top plan view on an enlarged scale;
FIG. 3 is a right edge view, the left edge view being a
mirror image thereof;

FIG. 4 is a bottom plan view;

FIG. 5 is a rear edge view; and

FIG. 6 is a front edge view.

The broken line showing of a shoe is for illustrative
purposes only and forms no part of the claimed design.

FIG. 1.

FIG. 2.

FIG. 3.

FIG. 4.

FIG. 5.

FIG. 6.
